UNITED STATES PATENT OFFICE.

FRANK E. MOORE, OF ELLWOOD CITY, PENNSYLVANIA.

GRAVITY-CARRIER.

1,102,181.

Specification of Letters Patent. Patented June 30, 1914.

Application filed July 15, 1913. Serial No. 779,196.

To all whom it may concern:

Be it known that I, FRANK E. MOORE, citizen of the United States, resident of Ellwood City, county of Lawrence, State of Pennsylvania, have invented certain new and useful Improvements in Gravity-Carriers, of which the following is a specification,

My invention relates to gravity carriers and particularly to a type adapted for use in connection with a drop or lowerator in which one platform ascends while another platform descends.

The object of the invention is to provide a carrier for use in connection with a drop or lowerator and designed particularly for transporting stereotype plates from the platforms of the drop to a printing press.

A further object is to provide a carrier which will handle the plates rapidly and without injury to them.

Other objects of the invention will appear from the following detailed description.

The invention consists generally in various constructions and combinations, all as hereinafter described and particularly pointed out in the claims.

In the accompanying drawings forming part of this specification, Figure 1 is a plan view of a gravity carrier embodying my invention, Fig. 2 is a vertical sectional view through the shaft of the lowerator, illustrating the movement of the platforms for delivering the stereotype plates to the carrier, Fig. 3 is a sectional view on the line $y-y$ of Fig. 1, Fig. 4 is a sectional view on the line $x-x$ of Fig. 1.

In the drawing, 2 represents the shaft in which the drop or lowerator is arranged and 3 and 4 are comparatively short carrier sections comprising the platforms of the plate drops. These platforms are raised and lowered alternately by a cable 4' passing over suitable sheaves 4" at the top of the lowerator shaft. This lowerator forms no part of my present invention and further description and illustration thereof is unnecessary.

Opposite the section 3 I provide a carrier section consisting of rails 5, 6, 7 and 8, ar-

ranged in pairs and connected with one another by suitable cross bars 9 at intervals. Journalized in bearings in these rails are anti-friction rollers 10 forming a movable bed continuation of similar rollers mounted in 55 the section 3. Suitable braces 11 connect the cross bars 9 with one another and hold the rails against racking and twisting. The rails 5 and 6 are curved, as indicated in Fig. 1, but of course may be straight, if preferred, according to the direction the stereotype plate or other article is to be carried after leaving the drop. In front of the section 4 is a carrier of similar construction, which I will designate by the same reference numeral with the addition of the exponent "a."

The rails 8 and 5^a come together at a point marked A. Rails 12 and 13 are secured at one end to the rails 7 and 6^a and extend 70 parallel therefrom and terminate near the ends of the rails 6 and 7^a. Journalized in the rails 12 and 13 are rollers 14, centrally arranged with respect to the inner rollers of the initial section of the carrier and sufficiently long to receive a stereotype plate or other article coming from either branch of the carrier. Near the rails 7 and 6^a are guard rails 15, curved to correspond to the curvature of the carrier rails and extending 75 between the rails 12 and 13 and supported by brackets 16. The guard rails 15 converge after entering between the rails 12 and 13 and terminate at a point B, where a comparatively narrow space is provided between them, sufficient to allow the passage 80 of the edge of the stereotype plate. Guard rails 17, supported in a similar manner, are provided adjacent to the rails 6 and 7^a and extend to the point of termination of these 90 rails C. These guard rails, while operating to direct the stereotype plates and keep them in their proper position on the carrier rolls, will not damage the plates upon coming in contact with them. The rails 5 and 8^a are 95 extended and form the outer rails of the main carrier section 18, to which the stereotype plates are successively delivered and transported to the printing press or any other suitable point. These outer rails form 100

bearings for rolls 19 which are supported at their inner ends by a rail 20, the bearings alternating in position in the rail 20 and the rolls being arranged to lap by the ends of 5 the rolls 14 and also form continuations of the movable beds of the carrier branches. Guard rails 21 and 22 are also provided, diverging from one another near the termination of the guard rails 12 and 13 and merging 10 into the inner rails of the main carrier 18. With this construction the stereotype plate 23 passing from the platform drop upon one branch of the carrier, will move thereover opposite the point A and will pass 15 upon the rollers 14 with one edge between the guard rails 15 and emerging from between these rails will pass upon one side of the diverging rails 21 and be directed thereby over the rolls 20 to the single carrier 18 20 and from thence to any point desired. The platform drops operating alternately, it is evident that the stereotype plates will be delivered first to one branch of the carrier and then to the other, and the plates moving 25 over these branches will pass one after another onto the carrier 18 and be delivered thereby to the printing press or any other point desired.

I have shown this device adapted particularly for handling stereotype plates, but it may be utilized for other purposes where it is desired to transport articles successively over branches of the carrier from a lowering apparatus or from any other delivering 35 means.

I claim as my invention:—

1. The combination, with lowerator drops or carriers, of carrier sections forming continuations of the beds of said drops, and 40 whereto the articles to be transported are delivered alternately by said drops, a single carrier section wherein said first named sections merge, and guides for directing the articles passing over said first named sections onto said single section.

2. The combination, with the gravity carrier sections arranged side by side and each comprising side rails and anti-friction rollers journaled therein, a single gravity carrier section forming a continuation of said first named sections and into which said first named sections merge, and a guiding means for directing the articles passing over said first named sections onto said single section.

3. A gravity carrier comprising carrier sections arranged side by side, each comprising side rails and anti-friction means journaled therein and forming a moving surface for the articles placed on said carriers, the inner rails of said carriers merging into one another at a point intermediate to the ends of said carriers, a carrier section forming a continuation of said inner rails be-

tween the outer rails of said carriers and 65 having anti-friction rollers adapted to receive the article from either one of said carrier sections, a single gravity carrier section connected with said first named sections and means for guiding the articles 70 onto said single carrier section.

4. A gravity carrier comprising carrier sections arranged side by side, each having side rails and anti-friction means mounted therein forming moving surfaces for the 75 articles placed on said carrier, the inner rails of said carrier sections converging to a point near one another, a carrier section forming a continuation of said rails and having anti-friction rollers journaled therein, said inner rails being spaced apart sufficiently to allow the edge of a stereotype plate to pass between them coming over either carrier section, a single carrier section and a guide having diverging rails arranged 80 to direct the stereotype plates upon said single carrier section.

5. A gravity carrier comprising carrier sections arranged side by side and having converging inner rails, a carrier section having comparatively long anti-friction rollers journaled therein forming a continuation of said inner rails and located between the outer rails of said carrier sections, similar carrier sections also having comparatively long 95 anti-friction rollers forming continuations of said outer rails, a single carrier, and guides mounted to direct articles from said first named carrier sections over said intermediate sections upon said single carrier 100 section.

6. A gravity carrier comprising sections arranged side by side and having anti-friction rollers journaled therein adapted to receive and transport semi-circular stereotype 105 plates placed thereon, a single carrier section forming a continuation of said first named sections, and diverging guides arranged to engage the stereotype plates and direct them from either of said carrier sections upon 110 said single section.

7. A gravity carrier comprising carrier sections, each having side rails and inner and outer groups of anti-friction carrying members journaled in said rails, a single carrier section having side rails and carrying members journaled therein, the outer groups of carrying members of said first named sections merging into the carrying members of said single section, the inner groups of carrying members of said first named sections converging and uniting into a carrier section intermediate to said outer groups, and guiding means above said intermediate carrier section for receiving the articles from 120 said first named carrier sections and directing them upon said single carrier section.

8. A gravity carrier comprising carrier

sections, each having side rails and anti-friction means mounted therein forming moving surfaces for the articles placed on said carrier, a carrier section forming a continuation of said first named sections and having anti-friction means mounted therein, a single carrier section, and a guide having diverging rails arranged to direct the arti-

cles from either of said first named carrier sections upon said single carrier section. 10

In witness whereof, I have hereunto set my hand this 27th day of June 1913.

FRANK E. MOORE.
